DESIGN FOR A COMBINED BUMPER GUARD AND FOG LIGHT HOUSING

Edwin F. Rygasewicz, Santa Monica, Calif.

Application January 6, 1948, Serial No. 143,543

Term of patent 7 years

(Cl. D14—6)

To all whom it may concern:

Be it known that I, Edwin F. Rygasewicz, a citizen of the United States, residing at Santa Monica, in the county of Los Angeles and State of California, have invented a new, original, and ornamental Design for Combined Bumper Guard and Fog Light Housing, of which the following is a specification, reference being had to the accompanying drawing, forming a part thereof.

Figure 1 is a perspective view of a combined bumper guard and fog light housing showing my new design. The broken line showing in Figure 1 is for illustrative purposes only.

Figure 2 is a front elevation of the combined bumper guard and fog light housing of Figure 1.

Figure 3 is a view in side elevation thereof.
Figure 4 is a view in rear elevation thereof.

I claim:

The ornamental design for a combined bumper guard and fog light housing, substantially as shown and described.

EDWIN F. RYGASEWICZ.
